UNITED STATES PATENT OFFICE.

JOHN HENRY WATTERS, OF AUGUSTA, GEORGIA.

TRACK-SANDER.

957,019.

Specification of Letters Patent.

Patented May 3, 1910.

Application filed January 13, 1910. Serial No. 537,808.

To all whom it may concern:

Be it known that I, JOHN HENRY WATTERS, a citizen of the United States, and a resident of Augusta, in the county of Richmond and State of Georgia, have invented a certain new and useful Track-Sander, of which the following is a full, clear, and exact description.

This invention relates to track sanders for use with locomotives or for other like purposes, and has reference more particularly to a device of this class comprising a nozzle member, adapted to be associated with a sand box, and having means for directing 10 two jets of fluid such as compressed air, one against the body of sand in the sand box and the other at an angle thereto, to cause the discharge of the sand from the sand box, the first jet serving to agitate the sand, a 15 movable valve member being associated with one of the jets.

The object of the invention is to provide a simple, economic and efficient track sander, by means of which sand can be discharged 20 smoothly and continuously from the sand box by means of a jet of fluid directed through a nozzle, in which sand is prevented from entering the nozzle to clog the same, in which a bridge or shelf is provided to 25 assist in the discharge of the sand from the sand box, which is so constructed that it can be expeditiously assembled and taken apart so that the device can be easily 30 cleaned, and in which is included a device 35 for purifying the fluid, such as air, which effects the discharge of the sand.

The invention consists in the novel construction and combination of parts to be 40 more fully described hereinafter and particularly set forth in the claims.

Reference may be had to the accompanying drawings, forming a part of this specification, in which similar characters of reference indicate corresponding parts in all 45 the views, and in which—

Figure 1 is a longitudinal section of an embodiment of my invention, showing the same applied to a sand box; Fig. 2 is a longitudinal section of the sander, showing 50 certain of the parts in plan; and Fig. 3 is a perspective view of the nozzle member for directing the jets.

Before proceeding to a more detailed explanation of my invention, it should be understood that the present form of the device

constitutes an improvement upon the track sanders shown respectively, in my United States Patents No. 785,284, dated March 21, 1905, and No. 803,258, dated October 31, 1905.

Certain of the details of construction, which form no part of the present invention, and which can be varied in accordance with individual preference or special conditions, are disclosed in the earlier forms of the track 65 sander, and the present invention resides largely in the valve member controlling one of the jets, and in the distributing and discharge-assisting bridge or shelf. While I prefer to employ air under pressure for operating the track sander, any other fluid adapted for the purpose, can be used.

Referring more particularly to the drawings, I have shown a sand box 10, of any preferred or common construction, having 75 therein the body of sand 11, used to increase the tractive effect of the locomotive wheels on the track rails, or for other purposes. The sander casing 12 is substantially of Y-form, and has a threaded end 13, arranged 80 in an opening of the sand box, and secured in place by a locking ring or collar 14, at the inside of the box. At the opposite end the casing has removably mounted therein a nozzle plug 15, of circular form, and provided with a lateral flange 32, seating 85 against the end of the casing. The nozzle plug 15 is held in position by means of a set screw 16. The sand discharge pipe 17 is associated with the casing 12 at a suitably 90 threaded opening thereof, under the plug 15. The latter has an extension 18 projecting into the casing toward the sand box, and of reduced diameter, the extension constituting the nozzle and having a passage 95 19 therethrough. Near the free end the nozzle has a reduced passage or opening 20, formed in a partition, and adjacent thereto a laterally-disposed inclined outlet or jet opening 21, alined substantially with the 100 discharge pipe 17, as is clearly shown in Fig. 1.

The nozzle at the free end forms a recessed valve seat 22, the inner end of which is rounded and which movably receives the 105 preferably spherical valve member 24, movably held in place by a transverse pin 25, constituting a stop to limit the movement of the valve member.

The nozzle plug 15 has a recess 26 formed 110

2
therein, which communicates with the passage 19, and is partly threaded to receive an annular threaded fitting 27, which constitutes a socket to receive the threaded end of the pressure supply pipe 28, through which the air or other fluid enters the nozzle. The inner end of the recess 26 forms a pocket in which is positioned a strainer 29, consisting of metal gauze, or any other suitable material, for purifying the fluid and freeing it from foreign substances.

Within the casing and preferably formed integral therewith, is a bridge or shelf 30, extending inwardly from the threaded end 13 of the casing under the nozzle member, so that it forms a substantially horizontal shelf to receive the sand as is indicated in Fig. 1. The bridge is preferably of tapered cross sectional form, and at the edge presents a lip 31, over which the sand passes to the discharge pipe 17. The fluid escaping through the opening 20 in the end of the nozzle, agitates the sand, and loosens it, the ball 22 regulating the jet for this purpose. It will be understood that the ball prevents the entrance of sand through the jet opening 20, and thus hinders the accidental clogging of the nozzle. The jet formed by the opening 21 creates a vacuum, under the influence of which the sand is drawn over the bridge and out through the discharge pipe 17. The bridge also prevents the escape of sand into the discharge pipe when the device is not in use, and no air is escaping from the jet opening 21. While the fluid jet impinges against the body of sand, and controlled by the valve member 24, is of assistance in the operation of the device, if the valve member should become inoperative the sand would still be discharged by the jet formed at the nozzle opening 21. Should the opening 21 become accidentally clogged, the movement of the valve member 24, which is very nearly in contact with the body of sand, would be sufficient to cause the sand to pass into the discharge pipe and thus escape. The contracted opening 20 of the nozzle member assists in reducing the fluid pressure, by permitting the expansion thereof, and the destructive sand blast is avoided thereby.

Having thus described my invention, I claim as new and desire to secure by Letters Patent:

1. In a track sander, a sand box, a casing opening therewith, and an air conveyer leading into said sand box and adapted to direct a stream of air against the body of sand in said box, said air conveyer having a passage of reduced diameter in advance of its discharge and having a movable valve member controlling said passage.

2. In a track sander, a sand box, a discharge pipe communicating with said sand box, and means for directing a jet of fluid into the body of sand in a direction oppo-

site to that in which the sand flows to the discharge pipe, said means having a movable, controlling valve member.

3. In a track sander, a sand box, a discharge pipe communicating with said sand box, and a nozzle for directing a jet of fluid into the body of sand in said box in a direction away from said discharge pipe, and opposed to the general direction of flow of the sand in discharging, said nozzle having a movable valve member controlling the jet.

4. In a track sander, a sand box, a discharge pipe, and a nozzle member having openings for directing two jets of fluid one against the body of sand in said sand box and the other toward said pipe to create a partial vacuum to cause a flow of sand into said pipe, said nozzle member having a valve member controlling one of said openings, said valve member being capable of limited movement.

5. In a track sander, a sand box having a discharge pipe, means for creating a partial vacuum within said pipe, and a nozzle having a loose valve member and serving to direct a jet of fluid against the body of sand at a point adjacent to the mouth of said pipe.

6. In a track sander, a sand box having a discharge pipe, a nozzle disposed adjacent to the mouth of said pipe and provided with openings for directing jets of fluid in different directions, said nozzle having a movable valve member controlling one of said openings, and a bridge under said nozzle, serving to direct sand to said discharge pipe.

7. In a track sander, a sand box, a casing communicating therewith, a nozzle member extending into said casing, and a discharge pipe communicating with said casing, said nozzle member having two openings, one for directing a fluid jet toward said sand box, the other for directing a fluid jet toward said discharge pipe, said nozzle member having at one of said openings a valve seat and movably associated with said seat a valve member having a limited movement.

8. In a track sander, a casing adapted to communicate with a sand box, a nozzle member extending into said casing, a discharge pipe communicating with said casing, said nozzle member having a passage therethrough and near the end of said passage an opening of reduced cross section, said nozzle member at the side of said opening remote from said passage forming a recessed valve seat, a valve member movably positioned at said seat, and a stop for limiting the movement of said valve member, said nozzle member at the side of said opening remote from said valve member having a laterally disposed opening communicating with said passage, said openings serving to form fluid jets.

9. In a track sander, a casing adapted to communicate with a sand box, a nozzle member extending into said casing serving to form fluid jets, and a discharge pipe communicating with said casing, said casing having an inward extension forming a bridge or shelf presenting a substantially horizontal upper surface, and a transverse lip at the free edge, above the entrance to said discharge pipe.

10. In a track sander, a casing adapted to communicate with a sand box, a nozzle plug removably mounted at said casing and having a nozzle member extending into the same, a discharge pipe communicating with said casing, said nozzle member having a passage therethrough and near the end of said passage an opening of reduced cross section, said nozzle member at the side of said opening remote from said passage forming a valve seat, a valve member mov-

ably positioned at said seat, and a stop for limiting the movement of said valve member, said nozzle member at the side of said opening remote from said valve having a laterally disposed opening communicating with said passage, said opening serving to form fluid jets, a supply pipe associated with said plug and communicating with said passage, and a strainer between said supply pipe and said passage, said casing having an inward extension forming a bridge presenting a transverse lip under said nozzle.

In testimony whereof I have signed my name to this specification in the presence of two subscribing witnesses.

JOHN HENRY WATTERS.
